UNITED STATES PATENT OFFICE.

GEORGE PULLMAN, OF NEW YORK, N. Y.

TIME RECORDER.

1,422,477.

Specification of Letters Patent. Patented July 11, 1922.

Application filed April 5, 1921. Serial No. 458,797.

To all whom it may concern:

Be it known that I, GEORGE PULLMAN, a citizen of the United States, residing at New York, in the county of New York, State 5 of New York, have invented a new and useful Time Recorder; and I do hereby declare the following to be a full, clear, and exact description of the invention, such as will enable others skilled in the art to which it app-

10 pertains to make and use the same.

The invention relates to time recorders and has for its object to provide a device of this character, which may be attached to a door and operated each time a lock carried 15 by the door is unlocked or locked, and the time of locking or unlocking the door lock, recorded on a time controlled dial. Also to provide means whereby the recording device may be operated by a watchman's key in- 20 dependently of the door lock, thereby recording the exact time the watchman inspected the door on his rounds.

A further object is to provide a rockable member having a piercing point at one of its 25 ends, said rockable arm being normally held outwardly at its upper end by a weight carried by its lower end below its pivotal point, and rocked inwardly when the lock is locked or unlocked, or when the watchman's key 30 is turned by a laterally movable member which moves outwardly and engages the lower end of the pivoted arm, thereby forcing its upper end inwardly for recording the time on a time controlled disc. Also to pro- 35 vide a pivoted member having a plurality of spaced arms, between which arms the pivoted time recording arm rocks, said spaced arms forming means whereby the pivoted arm which is slidably mounted on 40 a shaft may be positioned for piercing the recording dial at various points spaced from its center, thereby allowing the same recording dial to be used for a number of days, for instance for a week.

45 With the above and other objects in view, the invention resides in the combination and arrangement of parts as hereinafter set forth, shown in the drawings, described and claimed, it being understood that changes 50 in the precise embodiment of the invention may be made within the scope of what is claimed without departing from the spirit of the invention.

In the drawings:—

Figure 1 is a front elevation of the re- 55 cording device, showing the cover thereof open to better illustrate the structure.

Figure 2 is a top plan view of the time recording device, part being broken away to show the means for detachably securing a 60 time recording device to the inner face of a door.

Figure 3 is a side elevation of the device showing the same attached to a door and showing parts partly in section to better 65 illustrate the structure.

Figure 4 is a perspective view of the guide bracket for guiding the laterally movable operating plate outwardly.

Figure 5 is a perspective view of the 70 operating arm which is engaged by a vertically movable member operated by the lock or by a watchman's key.

Referring to the drawings, the numeral 1 designates a portion of a conventional form 75 of door and 2 the free edge of said door. The door 1 at its free end swings outwardly from the vertical side 3 of a conventional side of door frame 4. Secured to the door 1 in any suitable manner is a lock 5, which 80 lock has outwardly extending apertured lugs 6, which interengage with apertured lugs 7 of a keeper plate 8 carried by the vertical side 3 of the door frame, and with said apertured lugs the vertically disposed por- 85 tions 9 of a keeper 10, which also moves vertically when the lock is unlocked or locked, cooperate. The lock 5 may be pro- 90 vided with any suitable mechanism for moving the keeper 10 upwardly or downwardly and may be controlled by a key 11. Ex- 95 tending upwardly from the upper side of the keeper 10 is a vertically disposed shaft 12, the upper end of which is provided with a horizontally disposed head 13, which head is moved upwardly when the lock is locked and downwardly when the same is unlocked.

Secured to the rear face 14 of the door 1 is a plate 15, which plate at its lower end and sides is provided with channels 16 and 100 17, in which channels the flanges 18 of the time recording device 19 engage and is held, said time device 19 being held against upward movement by the pivoted dog 20, the lug 21 of which cooperating with a slot 22 105 in the plate 15. Disposed within the time

recording device 19 is a conventional form of clock mechanism 23, which clock mechanism rotates a disc 24 at a corresponding speed of rotation to the movement of the 5 hour hand of a clock. Disc 24 is provided with spaced prongs 25, which prongs pierce a paper dial 26, which is placed on the disc 24. Paper disc 26 has thereon radially disposed lines 27 indicating hours and intermediate graduations of any size desired may 10 be placed between the hour graduations. The paper dial 26 is also provided with concentrically disposed lines 28, indicating the different days in the week and form means 15 whereby the record for the complete week may be maintained on a single disc. If so desired pivoted arms 29 may be provided for overlying the paper disc 26 for preventing the same from bending downwardly.

20 Secured to the front face 30 of the casing of the time recorder is a bracket 31, in which bracket a horizontally disposed rockable shaft 32 is journaled and slidably and rockably mounted on said shaft 32 as at 33 25 is a rockable recording arm 34, the pivotal point of said arm 34 being intermediate its length, thereby providing an upwardly extending arm 35 and a downwardly extending arm 36. The upper end of the arm 35 is 30 provided with a piercing member 36, which when the arm 35 is forced inwardly pierces the paper dial 26 thereby recording on the paper dial the exact time of operation. The face 30 of the recorder is provided with a 35 horizontally disposed elongated slot 37 which allows the piercing member 36^a to pierce a hole in the paper dial 26. The lower end of the arm 36 is provided with a weight 37 extending outwardly, which 40 weight normally maintains the arm 35 in its outer position as shown in Figure 3 and the arm 36 in engagement with a laterally movable plate 38, said plate 38 being provided with headed lugs 39 which extend 45 through outwardly angled slots 40 of a bracket 41, which bracket is secured to the face 30 of the device. It will be seen that when the laterally movable plate 38 is moved to the left, that the headed lugs 50 which engage in the angularly disposed slots 40 will cause a laterally movable plate 38 to move outwardly in such a manner that the arm 36 of the recording arm 34 will be forced outwardly, thereby rocking the recording arm and forcing the arm 35 inwardly for recording the time of operation 55 on the paper dial 26.

The laterally movable plate 38 is normally held to the right as shown in Figures 60 1 and 2 by means of a spring 42, thereby allowing the recording arm to normally remain out of operative position as shown in Figure 3.

Pivotedly mounted in a bearing 43 of the 65 casing of the recorder is a rockable shaft 44.

Secured to the outer end of the rockable shaft 44 is a downwardly extending arm 45, the lower end of which is in the same vertical plane as the laterally movable plate 38 and is adapted to be moved in the direction of the arrow *a* for moving the laterally movable plate to the left during a recording operation. Extending downwardly from the rear end of the rockable shaft 44 which is adjacent the inner face of the door 1 is an arm 47, the lower end of which terminates in a vertically disposed portion 50, which portion is engaged by the flange 51 of a watchman's key 52, said flange 51 of the key engaging the vertical portion 50 of the arm 47, thereby rocking the shaft 44 and causing a recording operation to take place on the paper dial 26. It will be seen that every time the watchman makes his rounds that the time of inspection of the door will be recorded by the watchman by rotating the key 52. However, it is desirable to also have recorded on the paper dial 26 the exact time that the lock 5 is unlocked or locked, and to do this the downwardly extending arm 47 is provided with angularly disposed camming surfaces 53 and 54, with which surfaces the head 13 of the vertically movable shaft 12 engages, when the lock is unlocked and locked, whereby 95 causing the shaft 44 to be rocked and consequently the recording of the exact time of unlocking or locking the lock 5.

Hingedly connected as at 55 to the face 31 of the recorder is a horizontally disposed toothed plate 56, which is normally held down in horizontal position by means of a spring 57. The toothed plate has its teeth 58 spaced apart and disposed over the rockable shaft 32 and between any of said teeth 105 the arm 35 of the rockable recorder arm may be positioned for positioning the piercing member 36^a at various positions inwardly and outwardly from the tapered disc 26, thereby allowing the recording arm 34 to 110 be changed in position every day so that the same paper disc 26 may be used for recording a number of consecutive days, preferably for an entire week.

From the above it will be seen that a 115 time recording device is provided which may be easily and quickly attached and detached to a door and one wherein the time of inspection of the door may be recorded by the watchman and also the time the lock is 120 unlocked or locked.

The invention having been set forth what is claimed as new and useful is:—

1. A time recording device comprising a 125 casing, a time controlled movable disc carried by said casing, a vertically disposed and horizontally pivoted recording arm carried by the casing, the upper end of said recording arm being provided with a piercing member adapted to cooperate with a time 130

- controlled movable disc, the lower end of said recorded arm being weighted, said weighted end forming means for normally holding the upper end of the recording arm 5 outwardly, a horizontally disposed plate carried by the casing, means whereby said plate will move outwardly when moved in one direction for engaging the rockable recording arm and inwardly when moved in the 10 other direction, spring means for normally holding said plate in its inner position and means for moving said plate longitudinally and outwardly against the action of the spring means during a recording operation.
- 15 2. A time recording device comprising a casing, a time controlled movable disc carried by said casing, a vertically disposed and horizontally pivoted recording arm carried by the casing, the upper end of 20 said recording arm being provided with a piercing member adapted to cooperate with the time controlled movable disc, a horizontally disposed longitudinally and outwardly movable plate carried by the casing 25 and cooperating with the recording arm for forcing the piercing member carried thereby inwardly, said recording arm being longitudinally movable, a hinged and spring actuated horizontally disposed lug plate 30 carried by the casing, said lug plate being so positioned that the recording arm may be disposed between any of its lugs, and means for actuating the horizontally disposed longitudinally and outwardly movable 35 plate.
3. The combination with a time recorder comprising a time controlled movable disc and a horizontally pivoted and horizontally movable recording arm, of means for holding said recording arm in various positions, 40 said means comprising a hinged plate having a plurality of spaced teeth adapted to have disposed therebetween the recording arm.
4. The combination with a time recorder 45 comprising a time controlled movable disc and a pivoted recording arm pivotally mounted and longitudinally movable on a shaft, of means for holding said recording arm in various positions on the shaft, said 50 means comprising a toothed plate disposed adjacent the shaft and between the teeth of which the recording arm may be disposed.
5. The combination with a time recorder comprising a time controlled movable disc 55 and a pivoted recording arm pivotally mounted and longitudinally movable on a shaft, of means for holding said recording arm in various positions on the shaft, said means comprising a spring actuated toothed 60 plate disposed adjacent the shaft and between the teeth of which the recording arm may be disposed.

In testimony whereof I have signed my name to this specification in the presence of 65 two subscribing witnesses.

GEORGE PULLMAN.
